(57) CLAIM

The ornamental design for a packaging box with ball, as shown and described.

DESCRIPTION

FIG. 1 is a front perspective view of a packaging box with ball showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dot-dash lines immediately adjacent to the shaded area represent unclaimed boundaries and form no part of the claimed design. The broken lines shown represent unclaimed subject matter and form no part of the claimed design.

1 Claim, 4 Drawing Sheets
